UNITED STATES PATENT OFFICE.

JAMES F. TRAVIS AND WILLIAM H. FREANEY, OF NEW YORK, N. Y.

FRICITION-CLUTCH FOR DROP-LIGHTS.

SPECIFICATION forming part of Letters Patent No. 291,816, dated January 8, 1884.

Application filed August 25, 1883. (No model.)

To all whom it may concern:

Be it known that we, JAMES F. TRAVIS and WILLIAM H. FREANEY, both citizens of the United States, residing at New York, in the county and State of New York, have invented new and useful Improvements in Friction-Clutches for Drop-Lights, of which the following is a specification.

Our invention relates to that class of clutches in which wedge-shaped spring-impelled clamps are arranged in a suitable support to act on a sliding gasway, an adjusting-screw serving to regulate the position of the clamps; and it consists in a certain novel construction of the clamps, and in the combination therewith of anti-friction rollers, as hereinafter fully described and claimed, the whole being illustrated in the accompanying drawings, in which—

20 Figure 1 shows our clutch partly in side view and partly in longitudinal section. Fig. 2 is an edge view thereof. Fig. 3 is a perspective view of one of the clamps detached. Fig. 4 is an end view thereof. Fig. 5 is a sectional view on the line $x-x$, Fig. 1.

Similar letters indicate corresponding parts. The letter A designates a frame, forming a support for wedge-shaped clamps B—two or more in number—between which extends a 30 sliding gasway, C.

D indicates an adjusting-screw, passing upward through the lower part of the frame, to impinge against the lower ends of the clamps, so that by raising or lowering this screw the 35 pressure of the clamps on the gasway can be regulated according to the weight to be sustained. Said adjusting-screw D is tubular, thus allowing the passage of the gasway C through it, and above the clamps B is arranged 40 an impelling-spring, E, tending to force them downward. This spring, however, may, if desired, be omitted, since the clamps have a tendency to move downward by gravity. Each 45 of the clamps B is provided with a longitudinal recess, G, in the acting surface thereof, into which recess is fitted a packing, H, of felt or other suitable material, so that by the sides of the recess the packing is held against lateral displacement. The bottom of the recess G is 50 roughened, as by indentations s, Fig. 3, to

prevent the packing H from shifting longitudinally when the gasway is moved upward or downward, and in the body of each wedge are formed longitudinal channels I I, through which extends a cord, J, or the like, which 55 encompasses the end portions of the packing, and thus serves to fasten it permanently in position. Opposite to the channels I I each wedge is provided with grooves K in the opposite ends, into which grooves the cord J, together with the end portions of the packing, 60 is sunken, to afford a superior hold to the cord.

It will be noticed that by the arrangement of the packing H it can be readily taken off 65 from the clamps, so that it may be renewed when worn without affecting the other parts.

In the sides of the frame A are arranged rollers L, which form the bearings for the clamps or wedges, respectively, and serve to 70 relieve the wedges of friction, so that they are not liable to bind in the frame. In the example shown the frame A tapers downwardly; but when the anti-friction rollers L are used it may be straight, due to the fact that the 75 rollers alone form the bearings for the wedges. Said anti-friction rollers L are mounted on axial spindles N, which engage with cross-bars O, forming guards to prevent the wedges C from leaving the frame, so that the spindles 80 answer the additional purpose of holding such bars in position.

We are aware that it is not broadly new to arrange wedge-shaped clamps, lined with felt or other packing material, in a support to act 85 on a sliding gasway or tube, the clamps being adjustable vertically by a set-screw; and also that clamps arranged in a support to act on a sliding gasway or tube have been provided with inclined planes on their back, having 90 teeth engaging toothed wheels journaled in the support. Such features, therefore, are not claimed.

What we claim as new, and desire to secure by Letters Patent, is—

1. The wedge-shaped clamps, each having 95 a longitudinal recess in the acting surface and longitudinal channels in the body thereof, and having a packing, of felt or other suitable material, in such recess, fastened by a cord or the 100

like, passing through the channels, in combination with the supporting-frame and the adjusting-screw.

2. The wedge-shaped clamps, each having a longitudinal recess in the acting surface, longitudinal channels in the body, and grooves in the ends thereof, and having a packing, of felt or other suitable material, in the recess, fastened by cords which extend through the channels 5 and together with the end portions of the packing sink into the grooves, in combination with the supporting-frame and the adjusting-screw.
- 10 3. The combination of the frame, the wedge-

shaped clamps therein, the two cross-bars arranged outside the frame, and the friction-rollers journaled to the opposite ends of the cross-bars, and projecting into the frame to form the bearings for the clamps, substantially as described.

20 In testimony whereof we have hereunto set our hands and seals in the presence of two subscribing witnesses.
